Primary Examiner—Lucy Lieberman*(74) Attorney, Agent, or Firm*—Lars S. Johnson(57) **CLAIM**

The ornamental design for a bottle, as shown and described.

DESCRIPTION

FIG. 1 is a perspective view of a bottle showing our new design;

FIG. 2 is a front elevation of the bottle, the rear and side elevations are the same except for the placement of the indentations around the base of the bottle, which can be seen in FIG. 4;

FIG. 3 is a side view of the bottle depicted in FIG. 2 representing a partial rotation of the bottle about its vertical center axis from the front view depicted in FIG. 2; and,

FIG. 4 is a bottom view of the bottle depicted FIG. 2.

The broken lines showing the upper portion of a bottle are for illustrative purposes only and do not form part of the claimed design.
